UNITED STATES PATENT OFFICE

106,112

DESIGN FOR A HANDBAG

Alvin M. Ferrier, Lowell, Mass.

Application August 9, 1937, Serial No. 70,929

Term of patent 3½ years

To all whom it may concern:

Be it known that I, Alvin M. Ferrier, a citizen of the United States, residing at Lowell, in the county of Middlesex and State of Massachusetts, have invented a new, original, and ornamental Design for Handbag, of which the following is a specification, reference being had to the accompanying drawing, forming part thereof.

Fig. 1 is a side elevational view of a handbag embodying my new design;

Fig. 2 is an end elevational, and
Fig. 3 is a top plan view thereof.

The horizontal lines indicate that there is a contrasting color effect between the parts so lined and the other parts.

I claim:

The ornamental design for a handbag, substantially as shown and described.

ALVIN M. FERRIER.
